J. L. HENRY.
PROJECTILE FOR RIFLED ORDNANCE.
No. 35,824. Patented July 8, 1862.

UNITED STATES PATENT OFFICE.

J. L. HENRY, OF THE DISTRICT OF COLUMBIA.

IMPROVEMENT IN PROJECTILES FOR RIFLED ORDNANCE.

Specification forming part of Letters Patent No. 35,824, dated July 8, 1862.

To all whom it may concern:

Be it known that I, J. L. HENRY, of the District of Columbia, have invented a Projectile for Rifled Cannon, the nature of which will be described and shown in the following specification and drawings.

Figure 1 represents a section through its axis of rotation.

Two or more bands, a' a , of malleable metal, are secured around the projectile near its cylindrical termini. Soft iron will answer, or soft brass or copper. Beneath the rear parts of these bands are gas-channels b , of just sufficient capacity (and no more) to effect the desired end, as hereinafter set forth. Several channels, c , lead from these chambers to a central cavity, d , in the base of the projectile. This cavity's dimensions have been determined by experiment made by me to be about the size (for a six-pounder bore) shown in the drawings. Sufficient strength is thus given, and the center of gravity is thrown far enough forward to fulfill all the requisite conditions known to artillerists, and which are therefore omitted here.

The bands may be secured to the shot in any convenient and proper way. I have found in some, made by direction at the Washington Navy Yard, the following method to be good: An annular groove is turned in the shot, into which the front parts, i , of the bands are tightly forced, their ends merely meeting and need not be united; or, the groove may be larger, as at i' , and molten lead or other material may be pounded or swaged therein to secure them. In this case the parts i may be notched dove-tail shape, as at i' , Fig. 2. The molten metal will thus completely surround these parts and embed them. It is seen that the hinder parts only of the bands will be expanded by the gas to fit the bore and take the grooves or rifles of the gun, and as the quicker this expansion (for well-known reasons) takes place the better. The expanding parts should be thinned or otherwise weakened for this purpose. The rear edges are beveled, as at o , and fit against corresponding bevels around the shot. This supports them, and also allows the gas the more readily to escape from beneath them the moment they leave the gun—a very important consideration, since these rear edges will thus be expanded no more after leaving the gun; but if the gas were not to thus escape, or through

openings in them or around the bevel on the shot, it would force up the rear edges of the band higher than is necessary on leaving the gun, and would thus present considerable retardation to both rotation and translation. If these points be properly attended to, the band, after firing, will be found unchanged, except the slight wave-like appearance of their rear peripheries, caused by their "taking" the rifles of the bores, as seen in Fig. 3, which may be regarded either as a section of the bore or as an end view of the band after firing in a three-grooved piece.

For convenience, if the band be secured while casting the shot, they may be left standing out, as at v , Fig. 1, and after turning out the gas-chambers b (if these be not also cast) the parts v may be bent down into their finished or normal position. The bevels on the shot against which the rear peripheries of the bands rest may also be turned before bending the bands down into place.

In order that the gas may more readily escape from beneath the bands, these may be "scalloped" at intervals around their rear peripheries, or the beveled shoulders against which they rest may be thus scalloped for the same purpose.

To avoid the "chipping off" of small particles of the shot along the line of junctions between the shot and bands, the angles of contact on the shot should be "rounded off," as at n ; otherwise, on firing, small particles of the shot would be broken off by the expansion of the bands and left in the bore. This would injure the gun on the next fire. The bands at their bend o may be turned to snugly fit the bore, thus compelling the projectile (irrespective of expansion) to assume and keep axial position while passing from the gun, the first and last requisites for accuracy, as well as to prevent injury to the fiducial edges of the lands of the gun. This is better shown at Fig. 4. It is seen from this construction of shot, first, that a true axial position is secured to the projectile, which it keeps while passing out; second, that no vibration of the shot obtains in the bore; third, that windage is estopped, and that the shot is firmly supported in this position by means of the bearings of the bands at the termini of the cylindrical part; fourth, but half the number of grooves or rifles are necessary, as compared

with a shot having one band only; and it may be here remarked that three rifles about half inch wide and one-twentieth deep are sufficient.

A projectile having a single band extending nearly the entire cylindrical part, covered on its outer surface with a fibrous substance, was patented to R. I. Maryon, in England, in 1855. (See Patent No. 256 for that year.) This identical projectile was patented in the United States to Mr. C. T. James in February, 1856, the Patent Office, of course, not being aware of the English patent. The latter patentee (assisted by Mr. Floyd, Secretary of War) made extensive experiments, and many have also been made subsequently; but the fatal defects developed were principally two. First, the band having so great a surface exposed to the action of the gas is blown off in fragments just as the shot leaves the gun, in pieces weighing from a fraction of a pound to the weight of the band, which, of course, renders it dangerous to fire over or anywhere on the flanks of our own men, thus defeating the principal object of artillery—viz., to protect the different corps of troops in advance; secondly, the reaction of the band as it flies off deflects (of course) the projectile from its true path. But experiments made by me at West Point, New York, in 1857 and 1858, developed another serious defect—viz., a rapid and violent vibration of such shot, while passing out of the gun, causes it to "pound" or hammer the bore, thereby very much injuring it, and is another cause of inaccuracy. The cause of this is evident, when borne in mind that when such a band is expanded by the gas—from the shot against the bore—there is a "jacket" (or elastic cushion of gas) between it and that part of the shot it surrounds; hence the shot, by means of the action of the gas behind it, is rapidly and violently rocked longitudinally within this band so expanded, thus injuring the gun, as foreseen, and especially the "lands." Such shots are evidently worse than useless. To convert this shot into a shell, I need only explain my device for causing explosion on striking the target. A metallic plug, *k*, Fig. 1, having a corresponding chamber, *m*, receives a neatly-fitting piston, *p*, which is to be drawn out just before placing the shell in the gun, to drop a percussion pellet into the chamber, as shown in dotted lines at *s*. The piston is then reinserted partially, but is prevented from coming in contact with the pellet by a small elbow of wire, *t*, which is inserted in a hole in the piston, as shown. This wire is turned up parallel to the piston, as at *t*, and is received in a recess, *s'*, in the plug. This is its normal position; but when the piston is drawn out to insert the pellet this wire stop is turned down, as at *t'*, and, going into the recess *s'*, supports the piston clear of the pellet on firing. The shell is now inserted and pushed home by a cup-rammer, and when the target is struck the elbow-wire gives way, the pellet is exploded thereby, and fire is com-

municated through the vent *z* to the charge in the shell. The pellet may be inserted in a cavity in the plug, as in dotted lines at *q*, so as to drop itself into position when the piston is withdrawn.

When the percussion-cap to explode a shell is put in place while manufacturing it, I have invented the following safety device, (shown in Fig. 5, a longitudinal section thereof):

The percussion plunger or piston *A* has a "working fit" in a corresponding chamber in the nozzle of the shell, and may be retained in its normal position by a spiral spring or other device; or it may be independent of any such device, and be left free to move in its chamber. A nipple, *c*, is formed, as shown, by simply turning out a recess, *r*, about it, leaving the solid annulus *c'* flush with the cap when secured on the nipple. Through the screw-plug *a* an anvil-screw, *o*, is tapped, having such a pitch of thread as to cause it to advance about one-sixteenth of an inch at one turn. By inspecting the drawings it is seen that if the plunger *A* be forced forward by accident or otherwise, while the anvil-screw *o* remains as shown, the cap will not come in contact with said anvil-screw; but if this screw be advanced by a single turn, as shown in red, by an ordinary screw-driver, it will then receive the cap and explode it, when the piston is thrown forward upon the retardation of the projectile on striking the target, thus communicating fire to the charge in the shell through a vent in the piston, as in ordinary fowling-pieces. This anvil-screw is only thus advanced to receive the impulse of the piston just before inserting the shell into the gun.

It is apparent from the foregoing that accidental explosion of a shell is avoided beyond peradventure, and, on striking a target, its explosion is certain.

It is just and proper to remark that I have ascertained by investigation the approximate minimum volume of gas necessary to act beneath the bands to effect effective expansion, and no more. I have endeavored to show this proportion or relation between the force and the resistance to be overcome in my drawings for a six or eighteen pounder, and from this any artillerist may adapt it to larger calibers. Of course, if deemed less expensive, or more convenient for the cannoner when loading, instead of the anvil-screw, the anvil may be simply a smooth plug of soft metal—such as brass—and made rather larger—that is, slightly swelling—toward its outer end in such manner as to admit of being driven in by a blow on a proper "punch," as far, and no farther, than is necessary for the purposes set forth.

Having thus described my invention, what I desire to secure by Letters Patent of the United States is—

1. Combining one or more flexible bands with a projectile for rifled ordnance in any manner, substantially as described and shown, for the purposes set forth.
2. Two or more separate sets of gas-chan-

nels, *c*, leading from the cavity *d* in the base of the projectile to the under surface of two or more bands, combined with the projectile, substantially as and for the purposes set forth.

3. Causing a portion of the bands, as set forth, or the metal which secures them to the shot, to neatly fit the bore, for the purposes set forth.

4. The combination of an inflexible stop or rest with a concussion-piston, arranged substantially as set forth, for the purpose described.

5. The use of gas-chambers beneath a band or bands, so proportioned as to contain just sufficient gas to cause the band or bands to effect the end desired, for the reasons set forth.

6. Combining a percussion-piston with a shell, substantially as described and shown,

so as to render unnecessary a spring or other equivalent heretofore used to prevent accidental explosion.

7. Combining an anvil-screw or its equivalent with a shell in the manner substantially as shown, and for the purposes set forth.

8. The combination of the percussion-piston and anvil-screw with each other and with the shell, substantially as and for the purposes set forth and shown.

9. Combining a screw or its equivalent with a shell, so as to admit of being adjusted from the outside of the shell to explode the cap within, substantially as set forth.

J. L. HENRY.
